[57] CLAIM

The ornamental design for a housing for an upright pay telephone base, as shown and described.

DESCRIPTION

FIG. 1 is a front and right side perspective view of a housing for an upright pay telephone base showing my new design;

FIGS. 2 and 3 are respectively right and left side elevational views thereof;

FIGS. 4 and 5 are respectively top and bottom plan views thereof;

FIGS. 6 and 7 are respectively rear and front elevational views thereof;

FIGS. 8 and 9 are respectively perspective views thereof similar to FIG. 1 except for broken line showing of only a handset, its electric cord and a holder for the handset.

The broken line showing of only a handset, its electric cord and a holder for the handset on the base is for illustrative purposes only and forms no part of the claimed design.
